UNITED STATES PATENT OFFICE.

PETER L. HEDBERG, OF CHICAGO, ILLINOIS, ASSIGNOR TO CHICAGO METAL WEATHER STRIP COMPANY, OF CHICAGO, ILLINOIS, A CORPORATION OF ILLINOIS.

METAL WEATHER-STRIP.

1,033,694.

Specification of Letters Patent. Patented July 23, 1912.

Application filed February 24, 1912. Serial No. 679,726.

To all whom it may concern:

Be it known that I, PETER L. HEDBERG, a citizen of the United States, residing at Chicago, in the county of Cook and State 5 of Illinois, have invented certain new and useful Improvements in Metal Weather-Strips, of which the following is a specification.

This invention relates to improvements in 10 weather strips which are particularly designed for use on window casings, and it consists in certain peculiarities of the construction, novel arrangement, and operation of the various parts thereof, as will be hereinafter more fully set forth and specifically 15 claimed.

The principal object of the invention, is 20 to provide a weather strip, which may be carried in stock by merchants, and can be readily placed in position on the window 25 casing by unskilled persons so as to effectually exclude air and prevent side motion of the window sashes, whereby it will be adapted to correct ill fitting sashes and prevent them from rattling.

A further object of the invention is to 30 provide a combined strip of wood or molding and a metallic strip fitted thereon and thereto in about equal lengths, which 35 lengths may vary to correspond with the varying lengths of different sized window sashes, to the end, that the combined strip of molding and weather or metallic strip, of the requisite length may be purchased 40 from a merchant, and easily placed in position on a window by a person of ordinary skill.

Other objects and advantages of the invention will be disclosed in the subjoined 45 description and explanation.

In order to enable others skilled in the art to which the invention pertains, to make and use the same I will now proceed to describe it referring to the accompanying 50 drawing in which—

Figure 1, is a plan sectional view of a portion of a window casing and a part of the lower sash thereof showing a weather strip embodying one form of the invention 55 secured in operative position to the window frame. Fig. 2, is an enlarged perspective view of the form of weather strip shown in Fig. 1, illustrating the wood or molding strip shortened for the convenience of illus- 60 tration, and Fig. 3, is a similar view of like parts showing a modification in the construction of the strip.

Like numerals of reference refer to corresponding parts throughout the different views of the drawing. 65

The reference numeral 5, designates a portion of a window casing which may be of the ordinary or any preferred construction, and as usual is provided on the inner surface of each of its upright sides with a 65 groove 6, produced in any well known way, for the reception and vertical operation of each of the side rails 7, of the sash. The weather strip consists of a piece of molding 8, preferably of wood which is provided in 70 its surface adjacent to the sash rail 7, when the weather strip is in position on the window frame, with a longitudinally disposed groove 9, and on its surface opposite that adjacent to the window frame with a simi- 75 larly disposed groove 10, which grooves are by preference located at right angles to one another as is clearly shown in Figs. 1 and 2, of the drawings, and are of sufficient size to snugly hold parts of the metal strip, 80 which constitutes a portion of the weather strip and is fitted to the molding strip so as to be portable therewith, and if desired, adjustable thereon. The metal strip consists of a single piece which is bent to form 85 a channeled member 11, having on one of its walls a flange 12, which extends inwardly or toward the other wall of said channeled member. This flange is snugly 90 fitted in the groove 9, of the molding, and the other wall 13, of the member 11, is formed by bending the metal strip back upon itself or doubling the same and is snugly fitted in the groove 10, of the molding. 95 Thus it will be seen that a channeled member 11, rectangular in cross section is provided which will embrace the correspondingly shaped portion or part of the molding strip and securely connect the parts together. Extended from the outer layer or 100 fold of the wall 13, of the channeled member 11, alongside said member toward the sash 7, is a wing 14, of the metal strip which is formed integrally with the outer layer or portion of the wall 13, and extends longitudinally co-extensive therewith but is slightly spaced from the body of the channel 11, as 105 is clearly seen in Figs. 1, and 2, of the

drawing, unless forced thereagainst by the proximity of the sash rail 7, to the adjacent surface of the molding strip 8, which is secured to the wall of the frame 5, by means 5 of spikes or nails 15, driven through the same into the said frame. The wing 14, of the metal part of the strip has extended therefrom alongside the surface of the molding 8, adjacent to the sash rail 7, a flange 16, 10 which has near its free edge a deflected portion 17, which will rest against or contact with the surface of the rabbet or groove 6, of the window frame in which the sash rail 7, operates. By this arrangement it is apparent that, as the metal part of the weather 15 strip, is made of sheet metal which possesses considerable resiliency, the flange 16, having the deflected portion 17, at its free edge, to rest against one of the walls of the rabbet 20 of the window frame will serve to hold the sash rail 7, closely against the opposing wall of said rabbet in such a manner as to exclude the passage of air, dust, soot, moisture, and the like, and also, in such a manner 25 as to prevent lateral or sidewise movement of the sash rail, thereby preventing it rattling or producing noise.

In Fig. 3, of the drawing, a modification in the construction of the metallic part of 30 the weather strip is shown, which consists, in forming the outer wall of the channeled part or member 11, of a single layer or portion 13^a, instead of doubling the same, as in the other construction, and of folding 35 that portion of the single piece of metal out of which the metallic part of the weather strip is made, which forms the other wall 12^a, of the channeled part, or bending the same back upon itself longitudinally as 40 shown in Fig. 3, and providing its layer or portion adjacent to the window frame with a wing 14^a, to fit between the surface of the molding strip 8, adjacent to the sash rail 7, and to project at its free edge between one 45 of the walls of said sash rail and the wall of the rabbet 6, of the window frame adjacent thereto. In this modified construction, the wing 14^a, is provided with a deflected portion 17^a, at its free edge, which extends 50 co-extensive therewith, with a deflected part 17^a, which will rest against the wall of the rabbet 6, of the window frame and will prevent the admission of air and assist in holding 55 the sash frame in position within its guideway against lateral movement.

Having thus fully described my invention what I claim as new and desire to secure by Letters Patent is—

1. A weather strip consisting of a piece 60 of molding adapted to be secured to the surface of the window frame adjacent to the sash rails and provided on its surface adjacent to the sash rail with a longitudinally extended groove and in its surface opposite 65 that adjacent to the window frame a longi-

tudinally extended groove, and a single piece of sheet metal bent to form a longitudinally extended channeled portion having one of its walls located in the groove of the molding opposite the surface thereof adjacent to the window frame and its other wall located along the surface of the molding adjacent to the sash rail, the last named wall having an extension projecting toward the other wall of the channeled portion and located in the groove of the molding adjacent to the sash rail and a wing extended from said extension between the molding and sash rail and into the rabbet of the window frame. 70

2. A weather strip consisting of a piece of molding adapted to be secured to the surface of a window frame adjacent to the sash rail and provided on its surface adjacent to the sash rail with a longitudinally 75 extended groove and in its surface opposite that adjacent to the window frame a longitudinally extended groove, and a single piece of sheet metal bent to form a longitudinally extended channeled portion having one of its 80 walls located in the groove of the molding opposite the surface thereof adjacent to the window frame and its other wall located along the surface of the molding adjacent to the sash rail, the last named wall having an extension projecting toward the other wall of the channeled portion and located in the groove of the molding adjacent to the sash rail and a wing extended from said extension between the molding and sash rail. 85

3. A weather strip consisting of a piece of molding adapted to be secured to the surface of a window frame adjacent to the sash rail and provided on its surface adjacent to the sash rail with a longitudinally extended groove and in its surface opposite that adjacent to the window frame a longitudinally extended groove, and a single piece of sheet metal bent approximately back upon itself 90 to form a longitudinally extended channeled portion of two thicknesses of material and having one of its walls located in the groove of the molding opposite the surface thereof adjacent to the window frame and its other wall located along the surface of the molding adjacent to the sash rail, the last named wall having an extension projecting toward the other wall of the channeled portion and located in the groove of the molding adjacent to the sash rail, and a wing extended 95 from the outer layer of the last named wall between the molding and the sash rail. 100

4. As an improved article of manufacture, a weather strip consisting of a piece of molding having a pair of longitudinally 105 extended grooves, said grooves being located substantially at right angles to one another, and a single piece of sheet metal bent to form a longitudinally extended channeled portion having one of its walls located in 110

one of said grooves of the molding and its
other wall located along the surface of the
molding adjacent to the other groove there-
of, the last named wall having an extension
5 projecting toward the other wall of the
channeled portion and located in the last
named groove of the molding, and a wing

extended from said extension alongside the
surface of the molding in which the last
named groove is formed.
